[57] CLAIM

The ornamental design for a food service cart, as shown and described.

DESCRIPTION

FIG. 1 is a rear right perspective view of a food service cart showing my new design.

FIG. 2 is a top plan view thereof.

FIG. 3 is a bottom plan view thereof.

FIG. 4 is a right side elevational view thereof.

FIG. 5 is a left side elevational view thereof.

FIG. 6 is a rear elevational view thereof.

FIG. 7 is a front elevational view thereof.

FIG. 8 is a fragmentary top plan view thereof showing the right and left rear side wing tables raised.

FIG. 9 is a bottom plan view of FIG. 8.

FIG. 10 is a side elevational view of the support bracket taken on section line 10—10 of FIG. 9 it being understood that the support bracket is shown separately for the convenience of illustration.

FIG. 11 is a rear right perspective view of a second embodiment of the food service cart.

FIG. 12 is a top plan view of FIG. 11.

FIG. 13 is a bottom plan view of FIG. 11.

FIG. 14 is a right side elevational view of FIG. 11.

FIG. 15 is a left side elevational view of FIG. 11.

FIG. 16 is a rear elevational view of FIG. 11.

FIG. 17 is a front elevational view of FIG. 11.
